By atty. *Wm. H. Miller*

UNITED STATES PATENT OFFICE.

MAX ADLER, OF NEW HAVEN, CONNECTICUT, ASSIGNOR TO MAYER,
STROUSE & CO., OF SAME PLACE.

CORSET-CLASP.

SPECIFICATION forming part of Letters Patent No. 402,880, dated May 7, 1889.

Application filed February 18, 1889. Serial No. 300,239. (No model.)

To all whom it may concern:

Be it known that I, MAX ADLER, of New Haven, in the county of New Haven and State of Connecticut, have invented a new Improvement 5 in Corset-Clasps; and I do hereby declare the following, when taken in connection with accompanying drawings and the letters of reference marked thereon, to be a full, clear, and exact description of the same, 10 and which said drawings constitute part of this specification, and represent, in—

Figure 1, a face view of a pair of busks with a single clasp applied to one busk and engaged with a stud of the other busk; Fig. 15 2, a transverse section through the busks, showing edge view of the clasp engaged with the stud; Fig. 3, a face view, the outside plate removed to show the jaws; Fig. 4, a front end view of the clasp.

20 This invention relates to an improvement in devices for securing the front edges of corsets, and particularly to that class of fastenings in which the steels or busks are provided with clasps, the object of the invention being 25 to provide the clasps with a latching device which will automatically engage the two parts as they are brought together, and at the same time permit ready disengagement; and the invention consists in the construction, as hereinafter described, and particularly recited in 30 the claim.

A represents one busk, and B the second busk, which are of the usual construction, made from steel. The one B is provided with 35 the usual headed studs, C. To the other busk, A, and at points corresponding with the studs upon the busk B, two plates, a b, are applied, one each side the busk, and project from the clasping edge of the busk, so as to leave a 40 space between the two plates of substantially the thickness of the busk, which may be more or less. Between these plates two jaws, c d, are hung upon pivots e, and so as to swing between the plates in a plane parallel therewith. These jaws project from the edge of 45 the plates, their faces meeting, as seen in Figs. 1 and 3. The faces of the two jaws have a recess cut therein to form an opening, f, which corresponds in shape to the body of 50 the stud C, but of a diameter less than the diameter of the head of the stud. The nose

of each jaw from the opening f diverges, so as to form a flaring mouth, g, between the jaws into the opening f. From the pivots 55 the jaws are extended and turned outward, forming tails h, which project each side from between the plates, as seen in Fig. 1. These tails form handles or finger-pieces by which the jaws may be opened—that is to say, by pressing the two tails toward each other the 60 jaws will be opened, as indicated in broken lines, Fig. 3. The ends of these tails are turned outward, as indicated at i, Fig. 4, as a convenience for grasping the tails to thus open the jaws.

Between the plates and between the tails of the jaws a spring, l, is introduced, the tendency of which is to force the tails outward, and so as to bring the noses of the jaws together, as seen in Fig. 3, and yieldingly hold 70 them in that position. This completes the 75 clasp. It is applied to the busk, as shown, the two plates being riveted thereto, or otherwise secured, the edges projecting beyond the edge of the busk to an extent to reach the stud C on the other busk. To join the busks they are brought together. The stud, entering the flaring mouth g between the jaws, forces the jaws apart, the spring l yielding for that purpose until the stud enters the opening f 80 between the jaws. Then the spring reacts and brings the jaws together around the stud, and so as to retain the stud within their grasp.

To disengage the stud, it is only necessary to press the tails of the jaws toward each other, then the jaws open and the stud will escape. The engagement of the stud with the clasp is therefore automatic, produced simply by forcing the two parts together. No manipulation of the clasp is required for this 90 engagement, and this is a great convenience in securing the corset around the body. There is no force required to take the engaging devices beyond the position where they are to remain, as required in many cases, particularly in the usual slotted clasp, where the clasp must be forced over the stud to a considerable distance before the head can enter the slot, and then under reaction the clasp is drawn upon the stud. This same over-motion 95 is required in many of the interlocking clasps.

It is to be understood that I do not claim, broadly, a latch-like clasp on one busk adapted to engage a stud upon the other busk, as such, I am aware, is not new; but

5 What I do claim is—

A corset-clasp consisting of the two plates A B, secured to the busk upon opposite sides and projecting from the engaging edge of the busk, so as to leave a space between the projecting ends of the said two plates, combined with the jaws c d, hung upon pivots between the projecting ends of said plates, and so as to swing in the plane of the busk, the adjacent faces of the said jaws outside the plates

constructed with a recess corresponding to 15 the body of the stud with which the clasp is to engage, the noses of the said jaws outside the recess diverging to form a flaring mouth, the jaws extended from the pivots and turned outward to form handles h h, and a spring, 20 as l, between the tails of the jaws, which operates to yieldingly hold the jaws in their closed position, substantially as and for the purpose described.

MAX ADLER.
